UNITED STATES PATENT OFFICE

147,868

DESIGN FOR A BOX FOR LEADS OR THE LIKE

Jean O. Reinecke, Oak Park, Ill., assignor to
A. A. Sheaffer Pen Company, Fort Madison,
Iowa, a corporation of Delaware

Application January 7, 1946, Serial No. 125,336

Term of patent 14 years

(Cl. D58—12)

To all whom it may concern:

Be it known that I, Jean O. Reinecke, a citizen of the United States, residing at Oak Park, in the county of Cook and State of Illinois, have invented a new, original, and ornamental Design for a Box for Leads or the like, of which the following is a specification, reference being had to the accompanying drawing, forming a part thereof.

Figure 1 is a perspective view of a box of my new design;

Fig. 2 is a top plan view of the box shown in Figure 1;

Fig. 3 is a side elevational view of Fig. 2; and Fig. 4 is a bottom plan view of Fig. 3.

The dominant feature of my design resides in the elongated shape of the box with oppositely curved ends.

I claim:

The ornamental design for a box for leads or the like, substantially as shown and described.

JEAN O. REINECKE.
